UNITED STATES PATENT OFFICE

GEORGE J. MEYER, OF CUDAHY, WISCONSIN

OIL FEED MECHANISM

Application filed January 13, 1930. Serial No. 420,364.

This invention relates to improvements in oil distributing mechanisms.

The primary object of this invention is to provide simple means for distributing oil from a common source of supply to a series of bearings in quantities proportioned to the requirements of the respective bearings.

More specifically stated, the object is to provide an improved oiling system in which oil may be apportioned to the respective bearings and delivered in cycles of operations to a series of individual reservoirs capable of maintaining an adequate supply for an associated bearing during the period required for a completion of the cycle, under conditions favorable to inspection, the clearing of clogged ducts and the prompt elimination of any defect in operation.

Further objects are, to provide means whereby a pump may be employed to deliver definite charges of oil to an annular row of individual reservoirs, with which the pump outlet may be brought into registry by axial rotation of a reciprocating barrel or pump plunger; to provide means whereby the pump may be made to deliver excess charges, and the reservoirs permitted to over-flow and return excess oil to the source of supply, thus insuring the complete filling of each reservoir with a charge sufficient to supply the bearing throughout the period represented by the cycle; to provide means whereby multiple charges may be delivered by the pump to a single reservoir in successive operations of a pump plunger without variation in the duration of the cycle or the speed of the pump; and to provide means whereby the motion of the pump plunger may be transmitted to rotate the plunger step by step at intervals between oil delivering operations.

In general, the object is to provide a single oil distributing system which may be continuously operated mechanically, and which will be inexpensive, durable, and reliable for the stated purposes.

In the drawings:

Figure 1 is a plan view of an oiling system embodying the invention herein described.

Figure 2 is a sectional view, drawn generally to line 2-2 of Figure 1.

Figure 3 is a fragmentary elevational view of the rotary distributor, the individual cups, and associated parts.

Figure 4 is a fragmentary isometric view illustrating the operation of the ratchet cams and the manner in which they clear associated ratchet teeth.

Figure 5 is a diagram illustrative of the action of the cams.

Figure 6 is a view of a modified structure showing parts corresponding generally with those shown in Figure 3, but taken at right angles to the view shown in Figure 3.

Figure 7 is a fragmentary plan view showing a modification.

Like parts are identified by the same reference characters throughout the several views.

As a source of oil supply for the system herein disclosed, a glass container 10, preferably in bottle form, may be employed. The bottle is supported by a cage 11 in an inverted position, with its mouthpiece resting in a shallow cup 12, which has an outlet duct 13 leading to a suitable pump cylinder 14.

The pump cylinder is preferably vertically disposed and provided with a tubular plunger 15, the lower end of which receives a screw threaded, ported valve seat plug 18, provided with a check valve 19 at its upper end and having a guide stem 20 adapted to be lifted by the pressure of the oil during the down stroke of the plunger 15. During the down stroke of the pump plunger 15, a swinging check valve 21 in the passage 13 prevents the return of the oil that has been drawn into the pump cylinder 14 during the preceding suction stroke of the plunger, and a quantity of oil equal to that displaced by the plunger on the down stroke will be delivered through the outlet, viz., the ported arm or spout 23 and the depending nozzle 24.

The pump plunger 15 may be actuated,—reciprocated and rotatively adjusted,—from any suitable source of power. In the construction shown, power to reciprocate the plunger may be assumed to be applied through a reciprocatory actuating rod 26 (Fig. 2) in swivelled connection with the upper end of the plunger at 27, whereby the

plunger may be rotated as hereinafter explained.

The cylinder 14 supports an annular overflow chamber 30, preferably formed by an integral radially and upwardly projecting flange and having its upper marginal portion outwardly turned to form an annular cup supporting table 31. Upon this table, cups 32 are placed in an annular row, concentric to the cylinder and at a radius corresponding with that of the nozzle, a complete ring of cups being provided, with side walls integral or in contact, and over which the nozzle may be swung into registry with successive cups in a cycle of step by step movements, alternating with the oil delivering strokes of the pump.

The bottom of each cup has an outlet port 34 which extends through the table 31, where 20 by to communicate with a pipe 35 which leads to the bearing to be lubricated. The inner wall of each cup is preferably of less height than the outer wall and the side walls are inclined from the outer wall to the inner 25 wall, whereby any over-flow from the cups may be delivered inwardly.

The inner wall of the cup may also be provided with a spout 37 (Fig. 6) to carry the overflow across a rib 38 on the table 31, the 30 rib being preferably segmental. The upper surface of the table 31 may be slightly inwardly and downwardly inclined, whereby the cups may be uniformly positioned against the rib segments and the oil carried thereover, 35 not only by spouts 37, but also whereby any oil received on the surface of the table exterior to the rib may find its way between the rib segments to the inner side of the rib and into the collecting chamber 30.

40 The pump plunger 15 and the cups are relatively adjusted step by step rotatively. Where the cups are of normal size, each step movement should be sufficient to bring the nozzle into registry with the next cup in the 45 series whereby the succeeding down stroke of the plunger will deliver a charge of oil into that cup. Each cup is of a size adequate to supply the bearing with which it is associated with oil during the time required for 50 the pump plunger to complete its cycle and deliver another charge of oil to the same cup, and the pump capacity is sufficient to replenish the supply to a standard cup in a single pumping stroke.

55 If a bearing requires more oil than can be supplied by a cup of standard size, a double cup may be employed as indicated at 33 in Figure 1. This cup 33 is formed to occupy a space equal to that occupied by two cups 60 of normal size, whereby it may receive two charges of oil from a pump having a step by step movement equal in length to the distance between centers of two abutting cups of standard size.

65 If two charges of oil should be insufficient

to maintain the supply pending a return of the pump nozzle to any given cup, a cup of triple or of even greater size may be employed, although each larger sized cup should be a multiple of a standard size cup. This is 70 done in order that the pump plunger may be reciprocated in pumping strokes of equal length and speed, alternating with rotative step movements of equal length, co-incident with the retractive strokes, and thus avoid 75 complicating the mechanism by providing for variations in the character or degree of movement of the parts.

It is desirable that the retractive movements of the pump plunger may be transmitted and utilized to impart the rotative step by step movements. This is preferably 80 accomplished by providing the annular table 31 with inner and outer marginal ratchet teeth 40 and 41, respectively adapted to be 85 engaged successively by depending plunger rotating cam dogs 42 and 43. While any ordinary form of ratchet feed mechanism or other device for converting reciprocatory movement into rotative step by step movements might be employed, I prefer to employ the cam dogs illustrated, for the reason that they may be formed integrally with the nozzle, thereby simplifying the cost of construction, reducing repair requirements and the 90 possibility of failure in operation.

The form, arrangement and mode of operation of these cam dogs and their associated ratchets will now be described with reference to the specific structure illustrated.

The ratchet teeth may comprise mere pins or studlike projections in a horizontal plane. One of the dogs, e. g., the outer dog 43, is made with an offset shank portion 44 near the lower end of the shank, of sufficient length 105 and degree of offset to allow this portion of the shank to clear the end of an associated tooth 41 during part of the downward movement of the pump plunger, at which time the oblique surface 45 of the cam dog 42 will 110 bear upon the upper side of an associated tooth 40 and move the nozzle rotatively in the direction indicated by the arrow in Figures 1, 3 and 4.

Upon completion of the down stroke of the 115 plunger, both of the dogs will have been moved across the radial line of the teeth with which they are immediately associated, and the cam surface 46 of the dog 43 will occupy a position underneath the tooth 41 over the 120 end of which the offset portion 44 of this dog has just passed. Thereupon, an upward movement of the pump plunger will carry the cam surface 46 against the under side of said tooth 41, and impart an additional rotative movement to the nozzle and pump plunger until the cam surface 46 passes from beneath said tooth.

125 During this combined rotative and upward movement, the portion of the dog 42 130

having the oblique cam surface 45 will have been lifted above the level of the teeth 40 and also carried by the rotation of the dog carrier or nozzle into a position for engagement with the next ratchet tooth 40 during the succeeding downward stroke of the plunger. The arrangement of the parts is such that the dog 42 will first be lifted wholly above the tooth 40 which it is to engage and 10 then carried over it to a point where the lower end of the cam surface 45 will be in a position to engage such tooth while the plunger is moving on its downward stroke, thereby carrying the offset portion 44 of cam 15 dog 43 across the next tooth 40.

The cups will preferably be arranged upon the table in such a manner that the nozzle 24 will be carried across the dividing wall of two directly associated cups during the nozzle 20 moving operation of the cam dog 43. This movement occurs during the up stroke of the plunger, at which time no oil will be delivered. But the nozzle moving operation of the cam dog 42 should take place during 25 the downward movement of the pump plunger, at which time the nozzle outlet will be close to the cup with which it is in registry, or, if desired, slightly within the cup, to avoid splashing. The nozzle is thus moved 30 by the cam dog 42 across the central portion of the cup without coming into engagement with a side wall thereof, and if within the cup, the cam must be so disposed that the nozzle may be lifted out of the cup in time to 35 clear the wall over which it passes when again actuated by the cam dog 43.

Inasmuch as the ratchet teeth and the cam dogs may be formed integrally with the parts from which they are supported, it is 40 obvious that they may be formed of cast metal or that they may be cut, pressed or shaped from sheet metal. No manual operation for finishing or assembling will be required beyond fitting the valve seat and valve 45 to the plunger, associating the plunger with the cylinder, placing the cups upon the table, and connecting them with the oil ducts 35.

By employing a glass bottle 10 as a main reservoir, the quantity of oil in the reservoir 50 may be instantly determined upon inspection, and the supply renewed by substitution of bottles as frequently as may be necessary. Also, the delivery of oil into and from the cups may be observed, and if any passage is 55 obstructed so that a cup fails to receive oil or fails to allow it to normally flow through the outlet, this can be immediately detected during a single inspection of all the cups and the obstruction removed.

If desired, the table and associated parts 60 may be enclosed by a removable glass cap 49 through which the operation of the system may be inspected. In this manner dust may be excluded from the system. Oil over- 65 flowing from the cups will collect in the

chamber 30 and be returned to the supply cup 12 through a drain duct 50 (Fig. 2).

Within certain limits, a table 31 of a given diameter and with a given number of associated cups 32, may be employed for oiling systems having bearings, the number of which does not exceed the number of cups, except in cases where two or more bearings requiring little oil may be supplied from a single cup. In cases where the number of bearings 70 is less than the number of cups required to supply them, the oil outlets of unused cups may be connected to the main supply cup 12, or plugged and the cups allowed to overflow 75 into the chamber 30.

But in systems where the bearings to be lubricated exceed the number of the oil cups carried by a table of a given diameter, a table of larger diameter may be substituted, and the number of cups correspondingly increased 80 to any extent within the capacity of the pump to keep such cups supplied with oil. Larger systems will, of course, require pumps of increased capacity, tables of increased diameter and cups of correspondingly increased number. In such cases the speed of the pump may be increased to prevent undue extension of the time required to complete a given cycle or, if desired, the capacity of the cups and of the pump may be increased so that each cup will 85 receive a larger charge of oil and thus maintain the supply during the longer period of 90 the cycle.

As has already been indicated, the modified structure illustrated in Figure 6 differs from 100 that disclosed in Figure 1 principally by having the cups removable, whereas, in Figure 1 they are formed integrally with the table.

Referring to Figure 7 a further modification is illustrated in which the table is provided with but one row of teeth. The nozzle 23a carries a cam dog 43a substantially as disclosed in the other views and the ratchet teeth 41a correspond with the ratchet teeth 41 in the other views. But the pump plunger is 105 provided with an arm 53 which projects from the plunger on the opposite side from that occupied by the nozzle supporting arm 23a, and this arm 53 is provided with a cam dog 42a which acts upon the same ratchet teeth 41a with which the cam dog 43a engages. In this manner, a single row of ratchet teeth, associated with two alternately operating cam dogs, may be employed to advance the nozzle 110 in a manner similar to that in which it advances as disclosed with reference to the other views.

I claim:

1. An oil distributing mechanism including the combination of an annular table, an annular series of cups on said table, and provided with outlet ports, oil ducts, each connected with the outlet port of one cup, an axially disposed reciprocating pump plunger having an outlet nozzle adapted for registry 125

with the respective cups successively, and means for rotating the plunger to bring said nozzle into such successive registry with the cups on the table during retractive movements of the plunger.

2. Oil distributing mechanism comprising the combination of a pump plunger, a delivery nozzle associated therewith a pump cylinder in which said plunger is reciprocable an overflow chamber concentric therewith, an annular table having an inclined surface adapted to drain into said overflow chamber, an annular series of cups mounted on said table and each associated with an oil supply duct, and means for rotating the pump plunger and nozzle step by step to successively deliver oil to said cups.

3. An oil distributing mechanism comprising the combination with an annular table 20 provided with a series of oil cups, a pump having a nozzle rotatable step by step to deliver oil into said cups successively, a supply cup connected with the inlet of the pump and having a reservoir, the outlet of which is normally sealed in oil delivered therefrom to the supply cup, and oil feed ducts, each connected with one of the cups and adapted to convey oil therefrom to bearings to be lubricated.

4. An oil distributing mechanism comprising the combination with an annular table provided with a series of oil cups, a pump having a nozzle rotatable step by step to deliver oil into said cups successively, a supply cup connected with the inlet of the pump 35 and having a reservoir, the outlet of which is normally sealed in oil delivered therefrom to the supply cup, and oil feed ducts, each connected with one of the cups and adapted to convey oil therefrom to bearings to be lubricated, said cups being of standardized 40 dimensions and multiples thereof along the line of travel of the pump nozzle and each adapted to maintain a supply of oil to an associated bearing during one cycle of nozzle rotation.

5. The combination with an oil reservoir having a gravity feed and a pump supply cup in sealing relation to the reservoir, a pump having its inlet connected with the supply cup and provided with a check valve positioned to prevent return of oil to the cup, a vertically reciprocating pump plunger provided with a valved outlet passage and having a laterally and downwardly projecting nozzle near its upper end with which said passage communicates, means for reciprocating said plunger, ratchet mechanism for utilizing the reciprocatory movements of the plunger to rotate it step by step, and a series of oil cups disposed for registry of the nozzle therewith successively after each movement of step rotation.

6. The combination with an oil reservoir having a gravity feed and a pump supply cup 65 in sealing relation to the reservoir, a pump

having its inlet connected with the supply cup and provided with a check valve positioned to prevent return of oil to the cup, a vertically reciprocating pump plunger provided with a valved outlet passage and having a laterally and downwardly projecting nozzle near its upper end with which said passage communicates, means for reciprocating said plunger, ratchet mechanism for utilizing the reciprocatory movements of the plunger to rotate it step by step, and a series of oil cups disposed for registry of the nozzle therewith, successively, after each movement of step rotation, said ratchet mechanism including a set of dogs in fixed relation to the plunger and corresponding sets of ratchet teeth against which said dogs may bear during reciprocation of the plunger to impart step rotation to the latter, said dogs being disposed to act upon the ratchet teeth successively at times when the companion dog is in a position for engagement with the succeeding tooth in its associated series.

7. In an oil distributing system, the combination of a cup supporting table provided with a series of removable cups disposed side by side thereon and each having an oil conveying outlet duct and means for pumping oil into said cups successively in a cycle of pumping operations, said table having an associated overflow chamber, and said cups having overflow spouts disposed for delivery into said chamber.

8. In an oil distributing system, the combination of a cup supporting table provided with a series of removable cups disposed side by side on said duct and each having an oil conveying outlet duct and means for pumping oil into said cups successively in a cycle of pumping operations, said table having an associated overflow chamber, and said cups having overflow spouts disposed for delivery into said chamber, the table being inclined for drainage into said chamber.

9. The combination with an oil reservoir and an oil distributing chamber, each having a transparent wall, an annular series of individual cups located in the oil distributing chamber and detachably connected, each with an oil conveying duct, a centrally disposed pump having a nozzle revolute about the central axis of the pump, the nozzle outlet being at the radial distance of the cups from said axis and adapted for registry successively with said cups, means for actuating the pump for intermittent oil delivery and rotating it step by step in the interval between such deliveries to bring the nozzles into registry with successive cups.

10. The combination with an oil reservoir and an oil distributing chamber, each having a transparent wall, an annular series of individual cups located in the oil distributing chamber and detachably connected, each with an oil conveying duct, a centrally dis-

posed pump having a nozzle revoluble about the central axis of the pump, the nozzle outlet being at the radial distance of the cups from said axis and adapted for registry successively with said cups, means for actuating the pump for intermittent oil delivery and rotating it step by step in the interval between such deliveries to bring the nozzle into registry with successive cups, and an overflow chamber adapted to receive oil from overflowing cups and return it to the source of pump supply.

11. The combination with a plurality of serially disposed receiving vessels, of a delivery nozzle movable into successive stations in a path to deliver fluid into various of said vessels, means for intermittently delivering fluid from said nozzle into a vessel, and a device actuated by said means for moving said nozzle to a successive station whereby to insure such movement consequent upon each delivery.
